(57) **CLAIM**

The ornamental design for a lid for a container for food product, as shown and described.

DESCRIPTION

FIG. 1 is a top, side and front perspective view of a lid for a container for food product showing my new design;

FIG. 2 is a front elevational view thereof;

FIG. 3 is a side elevational view thereof from the right of FIG. 2;

FIG. 4 is a side elevational view thereof from the left of FIG. 2;

FIG. 5 is a rear elevational view thereof;

FIG. 6 is a top plan view thereof; and,

FIG. 7 is a bottom plan view thereof.

The material shown in broken line forms no part of the invention and is not claimed.
